UNITED STATES PATENT OFFICE

2,585,758

ELECTRIC IRON HOLDER

Odd Fjermestad, Brooklyn, N. Y.

Application June 4, 1949, Serial No. 97,166

1 Claim. (Cl. 38—107)

1

This invention relates to an electric iron holder.

It is an object of the present invention to provide an electric iron holder which can be connected by a cord to an electric source and to which the electric cord for the electric iron can be attached and also other electric elements can be connected thereto, the holder forming as well as a support for the electric iron a terminal box and means for releasably retaining the holder upon the ironing board.

Other objects of the present invention are to provide an electric iron holder with a terminal box, which is of simple construction, inexpensive to manufacture, has a minimum number of parts, compact, rigid, and efficient in operation.

For other objects and for a better understanding of the invention, reference may be had to the following detailed description taken in connection with the accompanying drawing, in which

Fig. 1 is a perspective view of an ironing board, the holder embodying the features of the present invention and the electric iron attached thereto.

Fig. 2 is a top plan view of the electric iron holder.

Fig. 3 is a sectional view taken generally upon line 3—3 of Fig. 2.

Fig. 4 is a transverse sectional view taken on line 4—4 of Fig. 2.

Fig. 5 is a transverse sectional view taken generally on line 5—5 of Fig. 3.

Fig. 6 is a transverse sectional view taken generally on line 6—6 of Fig. 3.

Fig. 7 is a transverse sectional view taken on line 7—7 of Fig. 2.

Referring now to the figures, 10 represents an ironing board on which a plate 11 is fixed by means of screws passing through holes 12 thereon. This plate has three struck up portions 13 adapted to receive a base portion 14 of the iron holder. The iron holder is thus removably connected to the base plate 11 on the ironing board.

The portion 14 is formed of insulating material, Fig. 4, and has connected to it by means of vertically extending bolts 15 separable insulating blocks 16 and 17 having openings 18 therein for receiving terminals or an electric socket 19 into which is extended an electric cable 21. The 50

2

separable insulating blocks 16 and 17 are also made secure by transversely extending bolts 22.

An iron holder receiving or supporting plate of metal is indicated at 23 and is made secure by means of the bolts 15 to the base portion 14. This plate 23 has a plurality of ribs 24 thereon. The plate also has a dropped supporting portion 25 which rests upon an insulating sheet 26 disposed across the top of the separable insulating blocks 16 and 17.

A cable 28 can be connected into one of the outward portions of the socket 19 for attachment with an electric iron 29 having the usual handle portion 31. An electric lamp or other device, as indicated at 32, may be connected through a cable to another outlet portion of the socket 19.

While various changes may be made in the detail construction, it shall be understood that 20 such changes shall be within the spirit and scope of the present invention as defined by the appended claim.

Having thus set forth and disclosed the nature of my invention, what is claimed is:

25 An electric iron holder comprising a base adapted to be attached to an ironing board, and having at least three struck-up portions, a bottom insulating portion removably received by the said struck-up portions of the base, separable insulating blocks secured to the insulating bottom portion, an iron receiving portion adapted to support an electric iron and secured to the said insulating blocks, said separable insulating blocks having openings therein, an electric socket fitted within said openings of the insulating blocks and having a plurality of outlets, one of said outlets receiving the electric plug of an ironing cord, a cable extending through the separable insulating blocks for supplying current to the electric socket therewithin.

ODD FJERMESTAD.
